DISPENSER RACK

Harold Bloomfield, Chicago, Ill., assignor to Bloomfield Industries, Inc., Chicago, Ill., a corporation of Illinois

Filed Aug. 17, 1960, Ser. No. 61,790

Term of patent 14 years

(Cl. D44—29)

Fig. 1 is a view in perspective of a dispenser rack, showing my new design;

Fig. 2 is a side elevational view thereof as seen from one position; and

Fig. 3 is a side elevational view thereof as seen from a position substantially at right angles to that of Fig. 2.

The broken line showings of condiment dispensers are for illustrative purposes only.

I claim:

The ornamental design for a dispenser rack, as shown and described.
